UNITED STATES PATENT OFFICE.

WILLIAM D. HALL, OF PHILADELPHIA, PENNSYLVANIA, ASSIGNOR, BY DIRECT AND MESNE ASSIGNMENTS, TO THE HALL MILK BOTTLE CAP COMPANY, A CORPORATION OF NEW JERSEY.

MILK-BOTTLE SEAL.

1,073,071.

Specification of Letters Patent. Patented Sept. 9, 1913.

Application filed August 21, 1912. Serial No. 716,251.

To all whom it may concern:

Be it known that I, WILLIAM D. HALL, a citizen of the United States, residing at Philadelphia, in the county of Philadelphia 5 and State of Pennsylvania, have invented new and useful Improvements in Milk-Bottle Seals, of which the following is a specification.

This invention relates to milk bottle seals, 10 the object of the invention being to provide a simple, inexpensive and reliable type of sealing disk which will maintain its shape and seal the bottle securely at all times while in use, and which may be conveniently extracted and also employed as an 15 advertising medium.

The invention consists of the features of construction, combination and arrangement of parts hereinafter fully described and 20 claimed, reference being had to the accompanying drawings, in which:—

Figure 1 is a vertical section through the upper portion of a milk jar showing the application of the invention. Fig. 2 is a perspective view of the seal removed and the flap turned up. Fig. 3 is a vertical transverse section through the seal in normal condition. Fig. 4 is a top plan view thereof.

Referring to the drawings, 1 designates 25 a milk jar or similar receptacle, the mouth of which is provided with an internal shoulder 2 adapted to serve as a support for the seal 3. The seal 3 comprises a pair of superposed disks 4 and 5 made of paper or 30 other suitable material and of proper size to fit within the mouth of the receptacle and rest upon the shoulder 2 to form a tight closure. Secured to the upper surface of the bottom disk 5 is a sheet or strip 6 of paper 35 or other suitable material on which any suitable advertising matter may be printed, which advertising matter may, however, be directly printed upon the disk 5, if desired. The disks 4 and 5 are pasted together or 40 otherwise suitably united, and arranged between the same is a reinforcing element 7, preferably consisting of a disk-shaped piece of woven wire gauze or other fabric, tape, tin, or other suitable material corresponding 45 in diameter to the disk, whereby the shape of the disks is preserved and the seal prevented from cracking, breaking or otherwise becoming injured or getting out of shape.

The top disk 4 is formed with a substantially keystone-shaped opening 8 normally

closed by an integral flap or finger piece 9 of corresponding form, the opening and flap being produced by suitably slitting the disk. The flap is integral with the upper or wider wall of the opening and at the lower or 60 narrower edge of the opening is provided a finger recess 10 to enable the nail of the finger to be inserted beneath the flap for the purpose of raising the same.

The reinforcing layer 7 is slotted to form 65 a portion 11 which is secured to the flap and forms a hinge whereby the flap may be opened and closed without breaking at a point of bend. This construction permits the seal, when made of durable material, 70 to be repeatedly used; and if desired the disks may be made of a water-proof substance to enable them to be cleansed without injury.

As is well known all prior seals of the 75 double disk or superposed layer type, in which the upper disk is slotted to form a finger tab or flap, are open to two main objections which impair their efficiency or render them inoperative as a seal for repeated 80 removal and re-application to a milk jar or like receptacle, to permit of the intervalar discharge of portions of the contents of the jar and its tight closure thereafter until the entire contents have been discharged. 85 Seals of this character when weakened by contact with the contents of the bottle or by external moisture lose their rigidity and are liable to bend, buckle or tear in the process of removing or applying them, with 90 the result that the jar is imperfectly sealed and the contents often spoiled. Again through the bending of the tab or flap from normal to extracting position, and back again, the flap is liable to break or tear at 95 its hinging point, causing it to break loose under the pulling strain thereon, which may be considerable in order to effect the extraction of the seal when the seal fits, as it should, tight enough to hermetically close 100 the jar. By my construction these objections are overcome, as by the use of the intermediate fabric layer the paper disks are reinforced and preserve their rigidity, while by partially removing and attaching 105 a portion of said layer to the tab or flap the latter is strengthened to a sufficient degree to prevent it from tearing loose and a hinging member provided which adapts the tab to be repeatedly opened and closed 110

without fracture along its line of bend. A seal constructed as above described will thus preserve its shape indefinitely and thus keep the bottle hermetically sealed to prevent access of air to the interior thereof. The strip 6 is so arranged that when the flap 9 is open the advertising matter thereon will be exposed, as shown in Fig. 2.

I claim:—

10. 1. A seal for receptacles comprising a pair of superposed disks, the upper disk having an opening and a flap adapted to lie therein, and a reinforcing element between the disks having a portion partially separated therefrom and connected to and movable with said flap.
20. 2. A seal for receptacles comprising a pair of superposed disks, the upper disk having an opening and a flap adapted to lie therein, and a reinforcing body of woven material between the disks and having a portion partially separated therefrom and connected to and movable with said flap.
25. 3. A seal for receptacles comprising a pair of superposed disks, the upper disk having a keystone-shaped opening and a correspondingly shaped flap adapted to fold therein, and a reinforcing disk of woven material between the aforesaid disks having a portion partially separated therefrom in line with said opening and connected to and movable with the flap.

4. A seal for receptacles comprising a pair of superposed disks and intermediate layer of woven material, the upper disk being provided with an opening therein and forming a flap partially separated therefrom, and the said intermediate layer having a corresponding portion partially separated therefrom and united to said flap and serving as a reinforcing hinge on which the flap is adapted to be opened and closed.

5. As a new and improved article of manufacture, a seal for receptacles comprising a disk formed of a pair of superposed paper layers and an intermediate reinforcing layer of woven material suitably united together, the upper paper layer being slotted to provide a finger tab adapted to be bent upwardly therefrom and downwardly into the plane thereof, and said intermediate layer being correspondingly slotted to provide a free portion secured to said tab and reinforcing the same and also serving as a hinging member, whereby said tab may be continually bent without separation from the disk along its line of bend.

In testimony whereof I affix my signature in presence of two witnesses.

WILLIAM D. HALL.
